EJECTOR FOR PERFORATING MACHINES

Joseph F. Ryan, Chicago, Ill., assignor to Cummins Perforator Company, Chicago, Ill., a corporation of Illinois

Application May 29, 1933, Serial No. 673,375

30 Claims. (Cl. 164—86)

The invention relates to perforating machines for receipting stub bills such as tax bills and those of public service and utility companies by perforating the date of payment and other data on the bills, and has more particular reference to an ejector for discharging the stub portion of the bill from the die opening of the machine into a locked receptacle or onto a table or desk.

An object of the invention is to provide ejecting mechanism for perforating machines which will be operated by stored energy derived from the action of the handle in performing the perforating operation and the actuation of which will be initiated to cause ejecting of the stub portion of the bill by the machine as the same completes the perforating operation. This mode of operation is important as it is necessary to have the ejecting action take place after the perforating operation has been completed in order that the punches will have been lifted from the openings clear of the paper.

A further object is to provide an ejector in which the ejector blade will have a close sliding fit in the die opening of the perforating machine to prevent even the thinnest bill stubs from becoming lodged above or below the ejector blade.

A further object is to provide novel means for locking the handle of the machine in the event the ejector blade becomes lodged in the die opening where serious damage would occur to the punching dies should a perforating operation take place.

A further object is to provide an automatic reversing lock for the handle requiring the operator to proceed with the perforating operation when once initiated by downward movement of the handle and to also continue upward movement of the handle to complete the operation after said movement has been started.

A further object is to provide ejecting mechanism for use in connection with perforating machines which will be simple in construction, positive in operation, and which will not easily get out of order.

With these and other objects in view, the invention may consist of certain novel features of construction and operation, as will be more fully described and particularly pointed out in the specification, drawings and claims appended hereto.

In the drawings which illustrate an embodiment of the device and wherein like reference characters are used to designate like parts.

Figure 1 is a front elevational view of a per-

forating machine showing the same equipped with the ejecting mechanism of the invention;

Figure 2 is a vertical sectional view showing in side elevation the mechanism for performing the ejecting operation;

Figure 3 is a horizontal sectional view taken through the die opening of the machine and showing the ejector blade and mechanism in top plan;

Figure 4 is a vertical sectional view taken substantially on the plane indicated by line 4—4 of Figure 2;

Figure 5 is a detail sectional view of the spring casing in unwound position;

Figure 6 is a view similar to Figure 5 showing the spring casing in wound position and locked by the locking lever; and

Figure 7 is a perspective view showing the type of bill perforated by the present form of perforating machine.

The perforating machine of Figure 1 comprises a base 10 having paper supporting surfaces formed by the die block 11 and an oscillating head 12 carrying a number of dies for perforating a bill with various data such as the date, the name or initial of the company, and other desired information, the date being changeable by adjustment of the pins 13. The oscillating head is suitably supported for movement from the base 10 of the machine and is operated by the handle 14 fixedly secured to the shaft 15, Figure 4, journaled in the projecting hub 16. With the handle in inoperative position, as shown in Figure 1, where it engages with the stop 17, the die opening 18 is unobstructed to permit the insertion between the punch holder 19 and the die plate carried by the block 11 of a bill or other form 20 to be perforated by actuation of the handle 14 downwardly causing downward movement of the selected dies in the head 12. Return movement of the handle lifts the dies to free the form, whereupon the same may be taken from the machine.

Perforating machines of the type described are commonly used to receipt bills upon payment of the same by the customer and in order that the company may retain a record of the payment the stub portion 21 is simultaneously perforated with the date and other information to indicate the employee operating the machine and the number of the machine. Simultaneously with the perforating operation the bill is severed on the dotted line 22 by the knives 23, the upper knife being operated by the oscillating head, while the lower knife is fixed to one of the paper supports 11. The present invention is more particularly con-

cerned with the automatic discharge of the severed stub portion of the bill since the main section of the bill is removed from the machine by the operator and returned to the customer. To prevent falsification of the records by the employee operating the machine the invention contemplates the provision of a locked receptacle associated with the machine in a manner to receive the ejected stub portions of the bill and which will prevent access thereto by the employees after the same has been perforated and severed as described.

The paper support 11 for the stub section of the bill is provided with grooves 24 on the respective sides thereof, receiving lugs 25 supporting for a close sliding fit over the surface 11 an ejector plate 26 having a right hand projecting portion 27, Figure 3, secured by rivets 28 to a reciprocating bar 30. Supporting means for the bar comprises a channel guide 31 supported horizontally from the machine by the member 32 and having retaining strips 33 suitably secured to the face thereof for retaining the bar while permitting reciprocating movements thereof.

The ejecting mechanism, Figures 2, 3 and 4, is confined between one side of the machine and a supporting plate 34 having an integral base portion 35 providing a flange 36 secured by screws 37 to the base 10 of the machine. The handle 14 fixed to the operating shaft 15, the outer end of which is journaled in plate 34, has secured to its hub portion by rivets 38 an inside cam plate 39 extending rearwardly and having secured thereto a pin 40. Also secured to the hub portion of the handle by the rivets 38 is an intermediate cam plate 41 carrying the release pin 42 and an outside cam plate 43, the function of which will be more particularly described.

Pivotedly secured to the base portion 10 of the machine is an oscillating lever 44 having an elongated slot 45 centrally thereof and an oblong opening 46 at its free end for receiving the pin 47 projecting from the bar 30. The reciprocating bar 30 through lever 44 has operative association with a spring casing 48 mounted for rotation on shaft 50 supported from plate 34 by the boss 51 to which the shaft is secured by the set screw 52, preventing rotation of the shaft. The spring casing houses a coil spring 53, the inner end of which is fixed to the shaft 50 by rivet 54 while the outer end of the spring is secured to the casing by the rivet 55. The plate 56 suitably secured to an internal shoulder formed in the casing provides the pivot pin 57 for the pawl 58 which is held in engagement with a notch in the disc 60 by spring 61 having one end secured to the free end of the pawl and the other end to the casing.

The disc held to the shaft by the thrust washer 62 suitably pinned to the outer end thereof is adapted to be frictionally engaged with plate 56, that is, with the spring housing 48, by the spring washers 63 and 64, interposed between the disc and the plate. Connection between the disc 60 and the oscillating lever 44 is effected by the pin 65 carried by the disc and which has location within the elongated slot 45 in the lever so that when a completed revolution of the disc takes place through rotation of the spring casing 48 the oscillating lever 44 will have movement from its extreme right hand position, as shown in Figure 2, to its extreme left hand position and return. This movement of the oscillating lever will reciprocate the bar 30 and thus the ejector plate 26 to cause discharge of the bill stub.

A feature of the invention resides in the means for rotating the spring casing one revolution, which includes a sliding rack bar 66 having a bifurcated end retaining a roller 67 and mounted for vertical sliding movement within the member 68 located to the inside of the supporting plate 34. To cushion the upward movement of the bar the member 68 is provided with a cap 70 secured to the supporting plate 34 by screws 71 providing a layer of felt 72 or like cushioning material as a stop for the bar. Meshing with the rack bar is a pinion 73 loosely mounted on shaft 50 and being secured to the spring casing 48, with the result that movement of the sliding rack bar 66 will cause rotation of the pinion and spring casing to wind the coil spring or to unwind the spring depending on the direction of rotation. The tension exerted by the coil spring causes clockwise rotation of the casing 48 and thus tends to maintain the rack bar in its "Up" position where it contacts with the cushioning stop 72.

The stud shaft 74 projects inwardly from the plate 34 and rotatably supports the locking lever 75 which is biased by the spring 76 so that locking relation is maintained between the lever and lug 77 to hold the casing in position with the sliding rack bar in engagement with the cushioning stop. Normally the locking lever is held out of engagement with the lug 77 by engagement of the release pin 42 with the lever, the pin being carried by the cam plate 41 on the handle and relatively positioned with respect to the handle so that the pin engages the lever to release the same when the handle is in raised inoperative position.

The operation of the ejecting mechanism is as follows: A bill or other business form to be perforated is first located in the machine and properly positioned by the paper stop 78 secured by screws 79 to the right side of the machine, Figure 1, whereupon the handle grip 14 is grasped by the operator and pressed downward to lower the handle 14, giving a counter-clockwise rotation to the cam plate 43, Figure 2. The cam plate engages with roller 67 on the sliding rack bar, forcing the same downwardly, rotating the pinion 73 and the spring casing in a counter-clockwise direction to wind up the coil spring 53. This rotation of the handle releases pin 42 from engagement with the locking lever 75, causing the lever to assume a locking relation with the casing. No interference, however, takes place between the lug 77 and the lever since the rotation of the casing is counter-clockwise. The effect of this rotation of the spring casing is to rotate the pawl 58 with respect to the disc 60, which is frictionally engaged and thus remains stationary as the friction of the spring washers 63 and 64 is not sufficient to initiate movement of the disc and the oscillating lever and reciprocating bar connection therewith. The extent of movement of the handle 14 to perform a perforating operation is sufficient to rotate the casing 48 a complete revolution which will bring the pawl 58 into engagement again with the notch in the disc 60 and the lug 77 into locked position with lever 75. Upward movement of the handle cause rotation of the cam plate 41 to again contact pin 42 with the locking lever 75, although engagement does not take place until the lever substantially reaches its inoperative position. Releasing the locking lever frees the spring casing and as the same has been wound by its counter-clockwise rotation above described, it proceeds to unwind, that is, to rotate in a clockwise direc-

150

tion. Any movement of the casing in this direction, however, positively carries with it the disc 60 as the pawl 58 has engagement in the notch in the disc, with the result that lever 44 is oscillated causing a reciprocation of bar 30 and the ejector plate 26 to discharge the bill stub. It is to be noted that the spring casing rotates one revolution and that the ejector blade has reciprocation forwardly of the die opening and then 10 rearwardly to its initial position out of the path of the punching dies.

The locked receptacle previously referred to is indicated at 80, being secured to the base 10 of the machine by threaded screws 81 and having a closure which may be locked by an official of the company, preventing anyone else from having access to the interior of the container. In accordance with the invention an opening in the box is positioned immediately adjacent the die opening 20 to receive the discharged stub bills automatically ejected by reciprocation of the ejector plate 26.

To prevent an incomplete operation of the perforating machine to perforate but only partially sever the same, whereupon the operator would be able to remove the entire bill from the machine and retain the stub portion, the invention provides a reversible locking pawl 82 rotatably mounted on the stud shaft 83 projecting inwardly from plate 34 and which is resiliently held in vertical position by the coil spring 84. The cam plate 43 is of rounded contour on the lower portion thereof, having a plurality of notches 85 formed therein, the end notches being of a width 30 to permit the locking pawl 82 to assume a vertical position, while the intermediate notches are of considerably less width thereby preventing rotation of the handle in both directions. The structure is reversible in operation, preventing upward movement of the handle until the full downward stroke of the same has been completed and in a like manner preventing any downward movement of the handle after upward movement of the same 40 has been initiated.

45 Serious damage would occur to the punching dies should a perforating operation take place with the ejector plate 26 lodged forwardly of the die opening and in order to prevent movement of the handle downwardly to perform a perforating operation, when such is the case, the invention provides the lever 86 pivoted to the base 10 as at 87 and having limited pivotal movement by reason of the pin 88 which is located within an arcuate slot 89 provided in the lower end of the lever. The free end of the lever is notched at 90 for engagement with pin 40 on the cam plate 39, the lever being biased by spring 91 to locate the parts in locked position where downward movement of the handle will be prevented. Projecting from one side of lever 86 is a stop 92 positioned for contact with a projecting end of bar 30 when the ejector plate 26 is located rearward of the die opening. It will therefore be seen that with the ejector plate in its rear position, where 55 a perforating operation can be performed without damage, the lever 86 is maintained in released position so that the pin is free of the lever and thus movement of the handle is possible.

From the foregoing it will be seen that the 70 invention provides ejecting mechanism for automatically discharging the stub portion of the perforated bill or other business form and which mechanism does not require extraneous motive power but is designed for operation by the same power means performing the perforating oper-

ation whether the same be by the hand of the operator or by a suitably connected electric motor. It will be appreciated that the movement of the ejector blade is rapid so as not to interfere with the perforating operation and which imparts sufficient momentum to the discharged stub portion to eject the same clear of the machine. This feature is principally secured by the spring-energized casing having the ability to store up energy and expending the same substantially instantaneously. The invention has been found to perform satisfactorily over a long period of time without requiring any adjustment whatever of the parts and even should a bill stub become lodged between the ejector blade and the top or bottom of the die opening to hold the plate in the path of the punching dies the operator would be immediately warned of the danger as the lever 86 would automatically engage with pin 40 to prevent further operation of the perforating machine.

It is to be understood that I do not wish to be limited by the exact embodiment of the device shown, which is merely by way of illustration and not limitation, as various and other forms 100 of the device will of course be apparent to those skilled in the art without departing from the spirit of the invention or the scope of the claims.

I claim:

1. In a perforating machine for stub bills or 105 similar business forms, the combination with an ejector for automatically discharging the stub portion of the perforated bill, and means locking the machine preventing a perforating operation when the ejector is in the path of the perforating 110 dies.

2. In a perforating machine for stub bills or 115 similar business forms, the combination with an ejector for automatically discharging the stub portion of the perforated bill, and means locking the machine preventing a perforating operation when the ejector is in the path of the perforating dies, said means being automatically released by the ejector assuming a position out of the path 120 of the dies.

3. In a perforating machine for stub bills or 125 similar business forms, a reciprocating ejector for discharging the stub portion of the bill, and means for actuating the ejector, said means being energized for each actuation by the machine in performing the perforating operation.

4. In a perforating machine for stub bills or 130 similar business forms, an ejector for discharging the stub portion of the bill, and means for actuating the ejector to discharge the stub portion and for returning the ejector to initial position, said means being energized for each actuation by the machine in performing the perforating operation, and being initiated by the action of the machine at the completion of said operation.

5. An ejector for a perforating machine for discharging a portion of the perforated form, including a reciprocating blade, and actuating means therefor, said means reciprocating the 140 blade forwardly to cause discharge of the bill portion and then rearwardly to initial position for every complete perforating operation.

6. An ejector for a perforating machine for 145 discharging a portion of the perforated form, including a reciprocating blade, and actuating means therefor, said means deriving power from the action of the machine in the first half of the perforating operation and being initiated to expend said power in reciprocating the blade by the 150

- action of the machine in completing the operation.
7. An ejector for a perforating machine for discharging a portion of the perforated form, including a reciprocating blade, and actuating means therefor, said means comprising a spring-energized member operatively connecting with the blade, and releasable means for holding the member in energized position.
10. An ejector for a perforating machine for discharging a portion of the perforated form, including a reciprocating blade, and actuating means therefor, said means comprising a spring-energized member operatively connecting with the blade, and being energized by the action of the machine during a perforating operation.
15. An ejector for a perforating machine for discharging a portion of the perforated form, including a reciprocating blade, and actuating means therefor, said means comprising a spring-energized member operatively connecting with the blade, connections from the member to the operating means for the machine whereby the member is energized by a perforating operation, and locking means for the member releasable by the action of the machine in completing an operation.
20. An ejector for a perforating machine for discharging a portion of the perforated form, including a reciprocating blade, and a spring motor for actuating the blade, said motor being wound by the action of the machine in perforating the form, and being released to reciprocate the blade by the action of the machine in completing the perforating operation.
25. An ejector for a perforating machine for discharging a portion of the perforated form, including a reciprocating blade, a spring motor, and connections between the motor and blade, said connections including a friction drive to permit winding of the motor while the blade remains stationary.
30. An ejector for a perforating machine for discharging a portion of the perforated form, including a reciprocating blade, a spring motor, and connections between the motor and blade, said connections actuating the blade when the motor unwinds but permitting the blade to remain stationary when the motor is wound up.
35. Ejector mechanism comprising, in combination, an ejector blade mounted for reciprocation, and rotating means operatively connecting with the blade to reciprocate the same, said rotating means including a casing rotatable on a fixed shaft, a convolute spring connected to the casing at one end and to the shaft at the other end, and locking means for locking the casing against rotation in one direction.
40. Ejector mechanism comprising in combination, an ejector blade mounted for reciprocation, a casing rotatable on a fixed shaft, a convolute spring connected to the casing at one end and to the shaft at the other end, locking means for locking the casing against rotation, and connections between the casing and blade operative to reciprocate the blade only when the casing rotates to unwind the spring.
45. Ejector mechanism comprising in combination, an ejector blade mounted for reciprocation, a casing rotatable on a fixed shaft and having means for rotating the same, and connections between the casing and the blade, said connections including a friction drive permitting rotation of the casing in one direction independently of the connections and also including a positive drive linking the casing with the blade to reciprocate the same when the casing rotates in the other direction.
50. Ejector mechanism for perforating machines comprising in combination, an ejector blade mounted for reciprocation in the die opening of the machine and adapted to eject the perforated forms upon reciprocation thereof, a spring motor for actuating the blade, means operatively connecting with said spring motor and being actuated by said machine in performing a perforating operation to wind said spring motor, and means locking the spring motor in energized position, said means being released by the action of the machine in completing the perforating operation thereby permitting operation of the motor and actuation of the ejector blade.
55. The combination with a perforating machine having a die opening and an operating handle, of ejector mechanism for discharging perforated forms from said die opening, including an ejector blade mounted for reciprocation in said die opening, a spring motor for actuating the blade, means operatively connecting with the spring motor and positioned for actuation by said handle in performing a perforating operation to cause winding of said motor, locking means for holding the spring motor in energized position, and means on said handle for releasing the locking means upon completion of a printing operation, whereby said motor operates to cause reciprocation of the ejector blade and discharge of the perforated form.
60. The combination with a perforating machine having a die opening and an operating handle, of ejector mechanism for discharging perforated forms from said die opening, including an ejector blade mounted for reciprocation in said die opening, a spring motor for actuating the blade, a rack bar mounted for vertical reciprocation and operatively connecting with said spring motor, said bar being depressed by the action of said handle in performing a perforating operation to cause winding of said spring motor, and connections between said motor and reciprocating blade, said connections including a friction drive permitting winding of the motor while the blade remains stationary.
65. The combination with a perforating machine having a die opening and an operating handle, of ejector mechanism for discharging perforated forms from said die opening, including an ejector blade mounted for reciprocation in said die opening, a spring motor for actuating the blade, a rack bar mounted for reciprocation and operatively connecting with said motor, said rack bar being reciprocated by the action of said handle in performing a perforating operation to cause winding of the motor, locking means for holding the motor in energized position, connections between said motor and reciprocating blade operative to permit winding of the motor while the blade remains stationary and to cause actuation of the blade by the unwinding operation of the motor, and means forming part of said handle for releasing the locking means to permit operation of the motor.
70. The combination with a perforating machine having a die opening and an operating handle, of ejector mechanism for discharging perforated forms from said die opening, including an ejector blade mounted for reciprocation in said die opening, a spring motor for actuating the blade, a rack bar mounted for reciprocation and operatively connecting with said motor, said bar

- being reciprocated by the action of said handle in performing a perforating operation to cause winding of said motor, locking means holding the motor in energized position, and connections between the motor and said reciprocating blade, said connections being actuated by the unwinding operation of the motor to cause reciprocation of the blade but operative to permit the blade to remain stationary while the motor is wound up, and means on said handle for releasing said locking means upon completion of a perforating operation. 80
21. The combination with a perforating machine having a die opening and an operating handle, of ejector mechanism for discharging perforated forms from said die opening, including an ejector blade mounted for reciprocation in said die opening, a spring motor for actuating the blade, said motor including a casing rotatable on a fixed shaft, resilient means connecting the casing to the shaft, a rack bar mounted for reciprocation and operatively connecting with said casing, said bar being reciprocated by the action of said handle performing a perforating operation to cause rotation of said casing, whereby said resilient means is energized, and connections from said casing to the reciprocating blade, said connections permitting rotation of the casing for energizing said resilient means while the blade remains stationary, and being operative to actuate the blade when said casing rotates in an opposite direction under the action of the resilient means. 90
22. The combination with a perforating machine having a die opening and an operating handle, of ejector mechanism for discharging perforated forms from said die opening, including an ejector blade mounted for reciprocation in said die opening, a spring motor for actuating the blade, said motor including a casing rotatable on a fixed shaft, resilient means connecting the casing and said shaft, means mounted for reciprocation and operative to cause rotation of said casing to wind up said resilient means to store up energy in the same, locking means for locking the casing in energized position, and connections between the casing and reciprocating means operative to cause actuation of the blade only when said casing rotates to unwind said resilient means. 100
23. The combination with a perforating machine having a die opening and an operating handle, of ejector mechanism for discharging perforated forms from said die opening, including an ejector blade mounted for reciprocation in said die opening, a spring motor for actuating the blade, said motor including a casing rotatable on a fixed shaft, resilient means connecting the casing and said shaft, means mounted for reciprocation and operative to cause rotation of the casing to energize said spring, locking means for locking the casing in said energized position, a disc rotatably mounted on said fixed shaft, a latch connecting the casing and disc to cause rotation of said disc when said casing rotates in a direction to unwind said resilient means, friction elements between the disc and casing permitting the casing to rotate while said disc remains stationary, and connections between said disc and reciprocating blade. 110
24. The combination with a perforating machine having a die opening and an operating handle, of ejector mechanism for discharging the perforated forms from the die opening, including an ejector blade mounted for reciprocation in the die opening, a pivoted lever operatively connecting with
- said blade, and power means for oscillating said lever to cause discharge of a perforated form from the die opening and to return the blade to its initial position, said motor being energized by the action of the handle in performing a perforating operation and being released by said handle at the completion of a perforating operation. 120
25. The combination with a perforating machine having a die opening and an operating handle, of ejector mechanism for discharging the perforated forms from the die opening, including an ejector blade mounted for reciprocation in the die opening, a spring motor including a casing and connections operatively connecting said casing with said blade, said motor being energized by means adapted to rotate the casing one complete revolution, and said casing rotating upon release of the same a complete revolution in the opposite direction to cause actuation of said reciprocating blade. 130
26. The combination with a perforating machine having a die opening and an operating handle, of ejector mechanism for discharging the perforated forms from the die opening, including an ejector blade mounted for reciprocation in the die opening, a pivoted lever operatively connecting with said blade, a spring motor for oscillating said lever including a rotatable casing operatively connecting with said lever, whereby a complete revolution of said casing will cause reciprocation of the blade forwardly of the die opening to discharge a perforated form and then rearwardly to locate the plate in its initial position, said motor being energized by rotation of the casing one complete revolution in a certain direction, and said casing rotating upon release of the same a complete revolution in the opposite direction to cause reciprocation of the blade forwardly of the die opening and rearwardly as described. 140
27. The combination with a perforating machine having a die opening and an operating handle, of ejector mechanism for discharging the perforated forms from the die opening, including an ejector blade mounted for reciprocation in the die opening, power means for reciprocating said blade, a locking lever associated with the handle and normally biased in a direction to prevent actuation of the handle for performing a perforating operation, and means adapted to reciprocate with said blade and operative to hold the locking lever out of locking position with the handle when said blade is located rearwardly of the die opening. 150
28. The combination with a perforating machine having a die opening and an operating handle, of ejector mechanism for discharging the perforated forms from the die opening, including an ejector blade mounted for reciprocation in the die opening, power means for reciprocating said blade, a locking lever associated with the handle and normally biased in a direction to prevent actuation of the handle for performing a perforating operation, means adapted to reciprocate with said blade and operative to hold the locking lever out of locking position with the handle when said blade is located rearwardly of the die opening, and locking means preventing partial operation of the handle in either direction. 160
29. The combination with a perforating machine having a die opening and an operating handle, of ejector mechanism for discharging the perforated forms from the die opening, including an ejector blade mounted for reciprocation in the die opening, power means for reciprocating said blade, a locking lever associated with the

handle and normally biased in a direction to prevent actuation of the handle for performing a perforating operation, means having reciprocation with said blade and operative to hold the locking lever out of locking position with the handle when said blade is located rearwardly of the die opening, a cam associated with said handle and having rotation therewith, said cam having a plurality of openings formed in its periphery, and a locking member associated with said openings, said member having operation to prevent a partial rotation of said cam and therefore said handle in either direction.

30. The combination with a perforating machine having a die opening and an operating handle, of ejector mechanism for discharging the perforated forms from the die opening, including

an ejector blade mounted for reciprocation in the die opening, a pivoted lever operatively connecting with said blade, power means for oscillating said lever to cause discharge of a perforated form from the die opening and to return the blade to its initial position, said motor being energized by the action of the handle in performing a perforating operation and being released by said handle at the completion of a printing operation, a cam associated with said handle and having rotation therewith, said cam having a plurality of openings formed in its periphery, and a locking member associated with said openings, said member having operation to prevent a partial rotation of said cam and therefore said handle in either direction.
